UNITED STATES PATENT OFFICE.

HENRY J. BRUGGEMAN, OF SIOUX CITY, IOWA.

FOLDING PASTEBOARD TRAY.

1,089,316.

Specification of Letters Patent.

Patented Mar. 3, 1914.

Application filed May 17, 1913. Serial No. 768,385.

To all whom it may concern:

Be it known that I, HENRY J. BRUGGEMAN, citizen of the United States, residing at Sioux City, in the county of Woodbury and State of Iowa, have invented certain new and useful Improvements in Folding Pasteboard Trays; and I do hereby declare the following to be a full, clear, and exact description of the invention, such as will enable others skilled in the art to which it appertains to make and use the same.

This invention relates to improvements in collapsible card board candy trays such as are used in packing candy and other articles easily mashed, and an object of the invention is to provide a tray of this character struck from one piece of material and having an upturned rim formed of individual members having novel locking means for securing the ends together.

A further object of the invention is to provide a tray, the upstanding rim of which is provided with means for locking in place the parting strips which serve to divide the tray into compartments.

A still further object of the invention is to provide a tray blank with rim flaps, the ends of which may be inturned to hold parting strips and in further providing locking tabs or flaps integral with the blank and adapted to fold over to lock the ends of the rim flaps and hold the same securely to the parting strip.

A still further object of the invention is to provide a candy tray having novel locking means in conjunction with the rim, this means being so formed as to transmit the pressure from superimposed trays directly to the trays beneath without in any way deforming the rims of locking members.

With these and other objects in view the invention comprises certain novel construction, combinations, and arrangements of parts as will be hereinafter more fully described and claimed.

In the accompanying drawings, wherein corresponding parts are designated by like reference characters, Figure 1 shows the blank from which the tray is formed, Fig. 2 is a perspective view looking into the top of the tray, Fig. 3 is a fragmental view of one of the locking members half closed, Fig. 4 is a view similar to Fig. 3 with the locking devices closed, Fig. 5 is a vertical section taken through the center of the tray and showing one of the locking devices, and Fig.

6 is a vertical section taken on lines 6—6 of Fig. 4 and looking in the direction of the arrows. Fig. 7 is a perspective view of a portion of the tray showing indent tabs in place for the reception of one end of the parting strip.

Heretofore, it has been proposed to use trays of the same general character as that disclosed herein for the purpose of packing candy or similar foods, the boxes in most instances being formed from a single blank and then a simple parting strip inserted but not held in place by any means integral with the tray. I am aware that it has been proposed to use boxes or trays of this general type wherein the parting strips are formed integral with the tray, but such parts require special machines for providing these parting strips, and also said parting strips are usually double and therefore require twice the amount of material actually required for the purpose of separating the tray into compartments.

My present invention aims to provide a simple tray readily assembled wherein the rim is formed of flaps having inwardly extending tabs adapted to be held together by flaps formed integral with the body of the tray and in placing between the tabs parting strips which will not only be held in place by the tabs but will also serve to coöperate with the means for locking the rim in place and for holding the rim more securely. In order to explain more fully the tray, reference may be made to the drawings and the following description, where the invention has been shown as applied to a circular tray, although it is to be understood that the tray may be oval, rectilinear, or in fact, any geometrical form which may be used for purposes of packing.

In the drawings, 1 designates the blank which, as shown in Fig. 1 is circular and has extending from four sides thereof rim flaps 2, the sides of these flaps being substantially at right angles when the blank is cut. Any number of these rim flaps could be used, but insomuch as in common practice it is sufficient to divide the tray into four compartments, it will be sufficient to provide four of these rim flaps. The ends of each of these rim flaps are provided with a tab 3 and there is provided between the tabs and the main part of the flap a line of scoring 4, which may be given the blank when the latter is cut from the sheet material, which may be card-

board or any other suitable material having the necessary rigidity for sustaining the weight of the contents of the trays. The lines of scoring 4 are not continuous but there is formed between the opposite edges of the flap 2 and in line of said scorings slits 5, the purpose of which will appear hereinafter. As shown in the blank, each of the ends of the several rim flaps is provided 16 with slots 6 and 7 located upon the upper and lower edges of said rim flaps respectively when the tray is assembled.

Extending radially from the blank 1 and lying between the adjacent ends of rim flaps 15 are locking flaps 8 each of which is provided with a line of scoring 9 between the flap and the blank, while there is provided an additional line of scoring 10 which is substantially parallel to the scorings 9, or if the 20 scorings are made curved, they will be concentric. As in the case of the scoring 4, the scoring 10 is not continuous but is interrupted by the slit 11 formed in each of the flaps 8, said slit 11 being substantially double the 25 length of the distance between the scoring 4 and the shoulder 12 formed by the slot 6 and the rim flap 2. Extending centrally from the slit 11 and radial with respect to the blank is an incision 13, the upper end of 30 which is enlarged so as to form a slot 14, while the inner end is enlarged to form a slot 15, which communicates with the slit 11. These slots 14 and 15 define tongues 16 and 17 of such length as to fit snugly into 35 the slits 5. The line of scoring 10 taken with the incision 13 defines a part of tabs 18 and 19 which are secured to the radial flaps 8.

The portions of the material which lie between the tabs 3 and the tabs 18 and 19, such as are indicated at 20 are removed, and an incision 21 formed in the blank for separating the tabs 3. Also, the parts of the material from which the blank is cut which lies between the body 1, the rim flap and the radial flaps are also removed, these portions being indicated at 22, while there is provided an incision 23 which separates the tabs 18 and 19 from the rim flaps 2 and their corresponding tabs 3. As shown in the drawings, when the portions 22 are removed, the inner edges 24 of the rim flaps are extended somewhat so that as the trays assemble, said edge 24 will extend below the top surface of the body 1 55 and rest directly upon the surface upon which the whole tray is supported. This edge 24 is separated from the slot 7 by means of a shoulder 25, which is so related with respect to the body 1 that when the 60 tray is assembled, said shoulder will engage the parts of the radial flaps indicated at 26.

In order to assemble the tray, the rim flaps 2 are each bent upwardly along the line of scoring 27 until the same are substantially at 65 right angles to the plane body 1. The flaps

3 are then bent inwardly along the lines of scoring 4, after which the ends of the rim flaps 2 are brought in to conform to the general outline of the finished tray. The lines of scoring 4 in the rim flaps 2 are so positioned that when the said flaps 2 are made to conform to the shape of the tray, the tabs 3 will just touch and will lie adjacent each other in parallel planes. This position of the tabs 3 is indicated in dot and dash lines 75 in Fig. 1, whereas the lines of scoring are made dotted to differentiate same from the lines showing position of the assembled rim flaps. In this position, the slits 5 are opposite each other and lie adjacent the rim of the tray. The radial flaps 8 are then bent upwardly along the line of scoring 9, after which they are further bent over the rim flaps 2 along the line of scoring 10, this position being shown in Fig. 3. The tabs 18 and 19 are then pushed downwardly to the position shown in Figs. 2 and 4, while the tongues 16 and 17 respectively lie in the slits 5. By this means, the rim flaps 2 are locked by means of the projecting radial 90 flaps 8 and the tabs 18 and 19 and by reason of the tongues entering the slits 5. It will also be noted that the portions of the upper edge of the rim flap 2 which lie between the shoulder 12 and the line of scoring 4 are 95 locked in the slit 11 and that the edge 24 lies in the plane of the bottom of the body 1. Further, the slot 6 is made of such depth that the bent portions of the radial flap 8 along the line of scoring 10 will be substantially in line with the top edge of the rim flap 2, and by these various means it will be seen that the pressure of the super-imposed trays will be transmitted directly to the lower trays without buckling or bending of 105 any part of the tray. The slots 14 and 15 are made of the width substantially double the thickness of the material from which the tray is cut so that when the tabs 3 are locked in the position shown in Fig. 4, the sides of 110 the slots 14 and 15 may lie against the tabs 3, the tongues 16 and 17 being thus deep enough to extend the full depth of the slits 5. In this way, the inwardly extending tabs 3 are securely locked in place.

In order to provide means for dividing the assembled tray in compartments, there is provided the requisite number of parting strips 28, two of these strips being shown in the drawing. These strips are of the proper 120 height so that their upper edges lie in the plane of the top of the tray and they are made of a length sufficient to extend between the radial flaps 8 when the latter are assembled. It will be noted by referring to the 125 dotted-line position in Fig. 1, that when the parting strips 28 are in place, the tabs 3 are spaced or separated a short distance, so that the tongues 16 and 17 of the tabs 18 and 19 respectively are forced apart and are 130

therefore bound to the parting strips 28. No particular method is shown for crossing the parting strips, insomuch as this feature forms no part of the present invention.

5. What I claim is:

1. A tray comprising a bottom, a multi-part rim extending from the body portion and having integral portions formed on the ends of the parts and extending inwardly of 10 the tray, and parting strips held by said inwardly extending members.

2. A tray comprising a body portion, a multipart rim extending from the body portion, adjacent ends of adjacent parts of the 15 rim meeting and extending inwardly of the tray, and parting strips held by the ends of said parts.

3. A tray comprising a body portion, a rim, tabs formed on the rim extending inwardly of the tray, parting strips held by said inwardly extending tabs, and means 20 integral with the body portion adapted to lock said tabs against the parting strips.

4. A tray comprising a body portion, a 25 multipart rim extending therefrom, the ends of the parts of the rim lying adjacent to one another, and means integral with the body portion adapted to fit over adjacent parts of the rim, and adapted to engage the ends of 30 said parts for locking the same.

5. A tray comprising a body portion, rim

flaps extending upwardly from said body portion, and having inwardly extending ends provided with slits, flaps extending from the body portion and having tongues 35 extending therefrom, said flaps adapted to extend over the ends of the rim flaps and have the tongues engage the slits.

6. A tray comprising a body portion, rim flaps extending upwardly from the body 40 portion and having inwardly extending ends provided with slits, flaps extending from the body portion, said flaps embracing the ends, tongues extending from the flaps and entering the slits, and a parting strip separating 45 said ends and tongues.

7. A tray comprising a body portion, rim flaps extending upwardly therefrom and having inwardly extending adjacent ends, flaps integral with the body portion adapted 50 to fit over the rim flaps and embrace the ends, means for interlocking the latter mentioned flaps with the ends, and a parting strip adapted to separate said ends and interlocking flaps.

55 In testimony whereof I affix my signature in presence of two witnesses.

HENRY J. BRUGGEMAN.
